UNITED STATES PATENT OFFICE.

WILLIAM H. CONNER, OF TOPEKA, KANSAS, ASSIGNOR TO CHAS. C. MADDY, OF OTTUMWA, IOWA.

HUMIDOR.

Application filed January 26, 1925. Serial No. 4,794.

My invention relates to a humidor. The objects of which are as follows:

First, to provide a device that will dispense moisture to cigars contained in an individual cigar box which device is attached thereto.

Second, to provide a mechanism of the construction shown, that will cause perfumes to exhume through clothing that is packed or otherwise stored.

Third, to provide a fluid container for the above purposes that may be inverted or tumbled about without spilling the contents.

Referring to the drawings,

Fig. 1—is an end view of the humidor having a cigar box mounted thereon parts broken away for convenience of illustration.

Fig. 2—is a fragmentary top view parts broken away for convenience of illustration.

Referring to Figures 1 and 2:

1 denotes a rectangular metallic box, shallow proportionately to its length and breadth which are slightly greater than those of a cigar box. Ears 2 are provided at the corners, to receive the corners of a cigar box, 3.

In the top and bottom of the box 1 are drilled a large number of holes, the relative arrangement of which is clearly indicated. Soldered to or within each of said holes is a short piece of tubing, 4 or 4'. Each tube 4 or 4' extends inwardly and stops short of the opposite wall of the receptacle. As shown, no tube will be in contact with any other.

The bottom E is held above the supporting surface by integral bosses 5, which permit free access of air to the orifices of the lower tubes 4'. This feature is not essen-

tial in a single-box humidor, but when the humidor is placed in a cigar case, cake box, or the like, the importance of this feature will be readily understood.

This humidor is charged with water by immersing it in water for only a sufficient time to admit a small quantity, as indicated in Figure 1, the top of the liquid being below the bottoms of the upper series of tubes.

A cigar box (3) is prepared for use on this humidor by removing its bottom. Thus the lower tier of cigars will rest upon the top of the humidor. The space disclosed between these is merely a diagrammatic feature of the drawing. Dry air enters through the lower tubes 4', takes up water vapor, and flows upward through the upper tubes 4 into the cigar box, wherein it fills all spaces around the cigars.

Cartons of cigarettes may be conditioned in the same way, after removal of the bottom of the carton.

It is to be observed that when charged with toilet water or perfume water, humidors of the construction disclosed may be placed in clothes cabinets, closets, chests or trunks, for the purpose of perfuming garments or fabrics stored in such places.

I claim—

In a humidor for individual cigar-boxes, a shallow rectangular casing including a perforated top and a perforated bottom, bosses on said bottom, and air tubes permanently fitted in all such perforations, said tubes extending vertically in said casing and those associated with the top and bottom respectively having their inner ends in different planes.

WILLIAM H. CONNER.
